UNITED STATES PATENT OFFICE.

WILLIAM MARX, OF WAUWATOSA, WISCONSIN.

DESIGN FOR A PATTERN FOR CHAIR-BACKS.

SPECIFICATION forming part of Design No. 22,327, dated April 4, 1893.

Application filed January 31, 1893. Serial No. 460,483. Term of patent 3½ years.

To all whom it may concern:

Be it known that I, WILLIAM MARX, of Wanwatosha, in the county of Milwaukee and State of Wisconsin, have invented and produced a new and original Design for the Ornamentation of Chairs, of which the following is a description, reference being had to the accompanying drawing, which is a part of this specification.

- 5 In the drawing A represents the top cross bar of a chair back showing my design thereon. The leading feature of the design is a profile head of Columbus, surrounded by a circle and fragments of a vine crossed below the circle and extending to the right and left thereof respectively. A curved space is provided within the circle adjacent to the arc of the lower half thereof adapted to receive a suitable inscription.
- 10 The design is intended to be carved or stamped and produced in relief on the top cross bar of a chair back.

The design is more particularly described as consisting of the profile head of Columbus, surrounded by the circle B, in connection with two fragments of a vine C C the stems of which are crossed below the circle centrally and extend therefrom toward the right and left beyond the circle, and have branches diverging therefrom, provided with leaves 25 30 thereon.

What I claim is—

The design for a pattern for the top cross bar of a chair back, substantially as shown and described.

In testimony whereof I affix my signature in presence of two witnesses.

WILLIAM MARX.

Witnesses:

JACOB CRIDER,
F. H. RYAN.
